UNITED STATES PATENT OFFICE.

ROBERT LOUGHER, OF PAPAIKOU, TERRITORY OF HAWAII.

DEVICE FOR REMOVING SUGAR FROM CENTRIFUGAL MACHINES.

1,105,444.

Specification of Letters Patent. Patented July 28, 1914.

Application filed May 28, 1913. Serial No. 770,453.

To all whom it may concern:

Be it known that I, ROBERT LOUGHER, a citizen of Great Britain, residing at Papai-
kou, in the county of Hawaii and Territory
of Hawaii, have invented new and useful
Improvements in Devices for Removing
Sugar from Centrifugal Machines, of which
the following is a specification.

This invention relates to a device or ap-
paratus for removing sugar deposits from
centrifugals after the molasses is purged
therefrom.

The primary object of the invention is to
provide a device or apparatus of this char-
acter which is simple and efficient in con-
struction and operation and by means of
which the sugar adhering to the sides of a
centrifugal basket may be rapidly removed
and discharged.

20 A further object of the invention is to
provide a sugar remover which may be
quickly and conveniently thrown into and
out of action and readily manipulated, and
which may be mounted and arranged for
25 adjustment to operate in connection with
two adjacent centrifugals, if desired.

The invention consists of the features of
construction, combination and arrangement
30 of parts hereinafter fully described and
claimed, reference being had to the accom-
panying drawings, in which:—

Figure 1 is a sectional perspective view of
two adjacent centrifugal machines, showing
the device arranged for operation in one of
35 the machines. Fig. 2 is a sectional view
through one of the machines, showing the
device supported in retracted or normal ele-
vated position. Fig. 3 is a sectional eleva-
40 tion, with a portion of the post broken
away, showing the raising and lowering le-
ver and certain features of construction.
Fig. 4 is a horizontal transverse section
45 through the horizontal track arm and parts
mounted thereon. Fig. 5 is a section on the
line 5—5 of Fig. 1. Fig. 6 is a detail sec-
tion showing the construction of the cut-
ting disk.

Referring to the drawings, A and B design-
50 ate two adjacent centrifugal machines, and
C and D, respectively the shell and rotary
basket of each machine. Supported in bear-
ing brackets 1, disposed between and se-
cured to the shells C, is a vertical post 2,
55 which is slidably and rotatably mounted in
said bearing bracket. At its upper end this

post carries an internally threaded bearing
member 3, supporting a horizontally ex-
tending track arm 4. This track arm is
preferably composed of a pair of spaced
rails, suitably fastened at their inner ends 60
to the bearing member 3 and suitably con-
nected and held in spaced relation at their
outer ends.

A carriage 5 is mounted to travel upon
the arm 4 and supports a vertically mov-
able bar 6, which is fitted to slide vertically
therethrough, but held from rotary motion.
This bar is provided with rack teeth 7 meshing
15 with a pinion 8 on the outer end of a rod or shaft 9. This shaft extends lon-
gitudinally of the track arm and is jour-
naled at its inner end in a hollow shaft 10
provided with external threads engaging
the threads of the bearing member 3. The
shafts 9 and 10 are respectively provided 75
at their inner ends with hand wheels 11
and 12 or other suitable means whereby they
may be adjusted. Stops 13 are provided on
the shaft 9 to hold it against longitudinal
motion with respect to the shaft 10, while 80
permitting it to revolve within and inde-
pendently of said shaft.

It will be understood from the foregoing
description that by means of the hand wheel
11 the shaft 10 may be rotated to travel for-
wardly or rearwardly in the bearing mem-
ber 3, in which operations it carries the
shaft 9 with it, whereby the carriage 5 and
bar 6 may be caused to travel along the track
arm 4. Also it will be understood that by 90
turning the hand wheel 12 the shaft 9 may
be independently operated to rotate the pin-
ion 8, whereby the rack bar will be vertically
adjusted. It will also be understood that
the post 2 may be vertically adjusted in the 95
bearings 1 to raise or lower the parts sup-
ported thereby, and is capable of being
turned or rotated in said bearings to swing
the arm and rack bar into different opera-
tive positions, as hereinafter described. 100

Fitted upon the lower end of the rack bar
is a guard or deflector 14 having a facing
15 of leather or other comparatively soft
material, and disposed in proximity to said
guard or shield is a rotary cutting disk 16. 105
This disk is of concavo-convex form and
preferably made of wood or other suitable
material and secured with metallic back-
ing plates or disks 17 to a hub 18, preferably
composed of threaded members between 110

which the disks and backing plates are securely clamped. The hub is mounted upon an axle pin or bolt 19 which is suitable secured to a shank or arm 20. The arm 20 is 5 adjustably mounted in an eye 21 formed upon one end of a bolt 22, which passes through the guard or shield 14 and lower end of the rack bar 6 and is provided with a clamping nut 23 whereby the parts are 10 firmly united. The shank 20 is adapted to fit within a recess 24 provided for its accommodation in the outer face of a head or washer 25 having an inner toothed face adapted to interlock with a correspondingly 15 toothed member 26 on the rack bar or deflector, whereby upon slackening the nut and bolt, the shank is rendered capable of longitudinal adjustment through the eye 21 and of vertical adjustment on the bolt as an axis, 20 and to be firmly clamped in adjusted position by screwing up the nut to tighten the bolt and throw the toothed members into locking engagement. By this means the cutting disk 16 is adapted to be adjusted 25 laterally with relation to the rack bar, and also to be adjusted vertically to vary its working angle.

The lower end of the post 2 seats within a 30 socket 27 pivotally supported by a treadle or foot lever 28 mounted upon a supporting bracket 29 fixed to the floor or any other suitable foundation. The post is adapted to drop by gravity through the bearings 1 to a lowered position, and may be elevated by 35 depressing the free end of the lever 28. The said free end of the lever 28 is adapted, when depressed, to be moved into engagement with a latch device or keeper 30, whereby the post may be held in an elevated 40 position while it is being turned or rotated on its axis. A U-shaped latch, keeper or holding member 31 may be provided upon the top or rim of the shell of each centrifugal to receive the arm 4 and lock the device 45 as a whole against swinging movements in the brackets 1 when the device is arranged in position for use within the centrifugal.

Fig. 1 shows the position of the device when disposed for use in the centrifugal A. 50 As indicated, the arm 4 extends inwardly over the shell of the centrifugal A and the rack bar 6 hangs down into the shell, thus supporting the cutting disk 16 in position to act upon the wall or body of sugar with 55 these adhering to the inner surface of the cage of the centrifugal after the molasses has been purged or withdrawn from the machine. When so disposed, the post 2 is lowered to engage the arm 4 with the keeper 31 and the rack bar 6 is initially lowered to 60 bring the cutting disk 16 and guard 14 close to the bottom of the pan and in proximity to the deposit of sugar. When so disposed the disk 16 is arranged at an angle with the 65 lowest portion of its cutting edge engaging

the body of sugar, its convex surface facing upwardly and outwardly, and its concaved surface facing inwardly and downwardly and toward the adjacent surface of the guard or deflector 14. When the parts are 70 so arranged, the centrifugal is thrown into operation to rotate the basket D, whereupon the disk will cut into the body of sugar and be rotated on its axis thereby cutting out the sugar in an effective manner. As the 75 disk cuts away the body of sugar the wheel 11 is turned to feed the carriage outwardly and adjust the disk laterally toward the wall of the basket, which action is continued until the deposit of sugar in the horizontal plane of the cutter is entirely removed. The disk is then adjusted inwardly by means of the wheel 11 and vertically to cut out the sugar at a high elevation, and this operation is continued until the whole of the sugar is 80 removed from bottom to top of the basket. This operation, of course, may be varied by allowing the disk to cut in a continuous vertical plane, while being elevated, from bottom to top of the basket, then causing it 85 to travel downward, and so on, until the sugar is removed. In its cutting action the dished or concaved side of the disk throws the sugar inwardly and away from the side wall of the basket and against the guard or 90 deflector 14, which guides it down toward the bottom of the cage for discharge through openings therein, the guard or deflector preventing the sugar from being thrown across the separator by centrifugal force, and insuring the rapid and free discharge of the 95 removed sugar through the outlet. After the removal of the sugar from the basket, the rack bar is elevated to raise the cutter and guard to the normally inoperative position 100 shown in Fig. 3, in which position the cutter and guard lie within the shell, but out of the way of the revoluble basket. If, after removing the deposit of sugar from the centrifugal A, it is desired to remove a deposit 105 of sugar from the centrifugal B, the operator then depresses the foot lever 28 and engages it with the keeper 30, thus lifting the cutter and guard clear of the first named centrifugal, allowing it to be swung by turning the post 2 in the bearings 1, for the use 110 of the device in the separator B.

It will be seen from the foregoing description that my invention provides a device or apparatus for removing deposits of 115 sugar from centrifugals, which provides a quickly acting cutter adapted to coöperate with a guard to feed the removed sugar toward the bottom outlet, thus insuring its quick discharge, and that the cutter is adjustable toward and from the guard, also vertically to vary its working angle, and is further adjustable vertically and laterally by the controlling mechanism acting upon the rack bar 6 to cut away the body of sugar 120 125 130

from top to bottom of the cage and until the surface of the wall of the cage is reached.

It will also be seen that the invention provides a device of this character which may be easily and conveniently operated, and which, if desired, may be employed in conjunction with two adjacent centrifugals.

I claim:—

- 10 1. In a device for removing deposits of sugar from centrifugals, the combination with a pair of adjoining centrifugals, of a support rotatably and slidably supported between the centrifugals, means for elevating said support, an arm carried by the support to extend over the top of a centrifugal, said arm being adapted by vertical and rotary adjustments of the support to be disposed over either of said centrifugals, a 15 guard adjustable on the arm, means for adjusting the same, a bar supported by the guard and adapted to depend into the centrifugal over which the arm is arranged, and a rotary cutter carried by said bar.
- 20 2. In a device for removing sugar deposits from centrifugals, the combination of a rotary and vertically adjustable support, an arm extending horizontally therefrom, a guard slidably adjustable on the arm, means 25 for adjusting said guard, a bar carried by and pendant from the guard, a concavo-convex cutter wheel supported by the bar to work at an angle thereto, and a guard carried by the bar and arranged in proximity 30 to the concaved face of the cutter.

3. In a device for removing sugar deposits from centrifugals the combination of a supporting post, an arm carried thereby, a carriage adjustable on the arm, means for 40 adjusting said carriage, a bar pendent from the carriage, means for vertically adjusting said bar, and a cutting disk carried by the bar.

4. In a device for removing sugar deposits from centrifugals, the combination of a post, an arm carried thereby, a carriage adjustable on the arm, means for adjusting said carriage, a bar pendent from the carriage, a dished disk cutter carried by said 50 bar, means for vertically adjusting the bar, and a guard or shield carried by the bar and arranged in rear of the concaved face of the cutter.

5. In a device for removing sugar deposits from centrifugals, the combination of a post, an arm carried thereby, a carriage adjustable along the arm, means for adjusting the same, a bar pendent from the carriage, means for vertically adjusting said 60 bar, a rotary dished cutter carried by the

bar, and a guard or shield upon the bar in rear of and in proximity to the concaved surface of the cutter.

6. In a device for removing sugar deposits from centrifugals, the combination of a post, an arm carried by the post, a carriage adjustable on the arm, screw gearing for adjusting the carriage, a bar pendant from the carriage, rack and pinion gearing for vertically adjusting said bar, and a cutter carried by the bar.

7. In a device for removing sugar deposits from centrifugals, the combination of a post, an arm carried thereby, a carriage adjustable on the arm, means for adjusting the same, a bar pendant from the carriage, means for vertically adjusting said bar, a shank carried by the bar, a dished cutting disk revolvably supported by the shank to work at an angle to the plane of the bar, and a guard or shield supported by the bar in proximity to the concaved face of the cutter.

8. In a device for removing sugar deposits from centrifugals, the combination of a post, means for raising and lowering the same, an arm carried by the post, a carriage adjustable on the arm, means for adjusting the same, a bar pendent from the carriage means for vertically adjusting said bar, and a dished rotary cutting disk supported by the bar.

9. In a device for removing sugar deposits from centrifugals, the combination of a post, supporting means in which the post is rotatably and slidably mounted, means for raising and lowering the post and holding the same elevated, an arm carried by the post, a support pendent from the arm and vertically and horizontally adjustable thereon, means for adjusting said support, and a cutter carried by said support.

10. In a device for removing sugar deposits from centrifugals, the combination of a post, means slidably and rotatably supporting the same, means for raising and lowering the post and holding the same elevated, an arm carried by the post, a support vertically and horizontally adjustable on the arm, means for adjusting said support, a cutter carried by said support, and means for holding the device from rotary movement on the post as an axis when said device is in a predetermined position.

In testimony whereof I affix my signature in presence of two witnesses.

ROBERT LOUGHER.
